UNITED STATES PATENT OFFICE.

WALLACE A. BARTLETT, OF WASHINGTON, DISTRICT OF COLUMBIA.

FIRE-EXTINGUISHING PROJECTILE.

SPECIFICATION forming part of Letters Patent No. 336,981, dated March 2, 1886.

Application filed September 7, 1885. Serial No. 176,342. (No model.)

To all whom it may concern:

Be it known that I, WALLACE A. BARTLETT, residing at Washington, in the District of Columbia, have invented certain new and 5 useful Improvements in Fire-Extinguishing Projectiles, of which the following is a specification, reference being had therein to the accompanying drawings.

This invention relates to projectiles of the 10 character specially intended for extinguishing fires.

The invention consists in the construction 15 of the main part of the casing of flexible material; also in the means for retaining the casing in extended position; also in means for rupturing the casing should the concussion fail to burst it on striking; also in certain details hereinafter set forth.

The principal object of the invention is to produce 20 a projectile adapted to the bore of a gun, which may be thrown into a fire from a steam or air gun, and which will be less dangerous as a missile than an inflexible projectile when thrown through a window or into a room which 25 is exposed to fire, in case the room have occupants.

Figure 1 is a longitudinal section of a projectile, showing the general arrangement. Fig. 2 is a side elevation. Fig. 3 is an elevation 30 of the flexible cylindrical casing. Fig. 4 is a front view, and Fig. 5 an edge view, of the head.

A indicates the cylindrical casing of oiled cloth, leather, rubber or rubber cloth, strong 35 paper, or similar material. A good material for the purpose is a short section of hose similar to that used for water. In most cases it is desirable that the casing be water-proof; but as I contemplate using chemicals in a dry state in 40 some instances, a casing of paper or an ordinary woven fabric may sometimes be employed. The cylindrical casing will be of such diameter as to easily enter the gun.

B indicates the head of the projectile, preferably 45 of cork or light wood, varnished on the inside, or of rubber. I have shown this as having a flat front; but the front may be in any form usual in projectiles, as in dotted lines, Fig. 1. The edge of the head has a 50 groove, C, into which the casing may be crimped. The head is of such diameter as to nicely fit the casing, to which it is cemented,

and may be further secured by a cord, D, which draws the casing down into the groove and serves to retain the head in place, as well 55 as to assist the cement in making a tight joint. The tail-block E is generally similar to the head, but has a perforation, F, through which the projectile is filled and a stopper, G, closes this mouth. A spreader, H, preferably of 60 light wood, extends from the head to the tail-block, serving to retain the casing distended. This spreader has a tenon, I, which enters a socket, K, in each end piece, or the projection and socket may be reversed. The head 65 B has a shallow recess, M, in its outer face, in which a small quantity of fulminate may be placed and secured by a bit of varnished paper. A light metal or pasteboard cap, O, having its edge held in groove P in the head, 70 protects this fulminate cap against slight blows; but when the projectile strikes the cover collapses and thus explodes the fulminate, assisting to burst the casing.

Instead of resting in a groove in the head, 75 the cover may fit over a projection. (See dotted lines.)

The projectile may be guided by fin or feather S, (dotted lines,) or in other manner 80 usual for retaining a projectile point on.

The projectile will be filled with a fire-extinguishing compound, either liquid or solid, and thrown into a fire or into a room liable to conflagration, from a gun of suitable construction, such, for instance, as described in my 85 Patent No. 308,945. The release of the liquid or gases in the projectile by the breakage of the casing on striking, or by the combustion of the casing should the projectile fail to break, will liberate the contents of the projectile, and tend to check combustion in proportion to the efficiency of the chemicals employed.

I claim—

1. A projectile having its inclosing-casing 95 composed mainly of flexible material and filled with a fire-extinguishing compound, substantially as described.

2. The combination, in a projectile of the character described, of a cylindrical casing of 100 flexible material, end pieces secured thereto, and a fire-extinguishing compound inclosed therein, substantially as described.

3. The combination, in a fire-extinguishing

projectile, of a cylindrical casing of flexible material, end pieces secured thereto, and a stiff spreader extending from end to end inside the casing.

5. 4. The combination, with an elongated projectile filled with a fire-extinguishing compound, of a fulminate cap at the front of said projectile, and a collapsible cover for said cap, as set forth.

10 5. The combination, with a fire-extinguisher projectile, of a detonator or exploding-cap attached to the outside of the casing in which the fire-extinguishing compound is inclosed.

6. The combination, with the flexible in-

15 closing-casing and stiff end pieces, of the rigid spreader having tenons resting in recesses in said end pieces, as set forth.

7. The combination, with the flexible cas-
ing having stiff end pieces and a central rigid
spreader between said pieces, of guiding 20
mechanism for the projectile, substantially as
described.

In testimony whereof I affix my signature in
presence of two witnesses.

WALLACE A. BARTLETT.
